HOUSING FOR ELECTRONIC APPARATUS

Edward R. Wiener, Rochester, Minn., assignor to International Business Machines Corporation, New York, N.Y., a corporation of New York

Filed Nov. 1, 1965, Ser. No. 87,958

Term of patent 14 years

(Cl. D26—5)

FIG. 1

FIG. 2

FIG. 1 is a perspective view of a housing for electronic apparatus showing my new design; and

FIG. 2 is a perspective view of a housing for electronic apparatus with several of the individual containers shown in the extended position.

The essential features of my design reside in the portion shown in solid lines.

This application is a continuation-in-part of the patent application by Edward R. Wiener, Serial No. D. 81,717, filed September 14, 1964, for Modular Containers for Electronic Components, now abandoned.

I claim:

The ornamental design for a housing for electronic apparatus as shown and described.
